APPARATUS FOR TREATING FLUID MATERIALS

Mead Cornell, Cleveland, Ohio, assignor to The Cornell Machine Company, Cleveland, Ohio, a corporation of Ohio

Application October 17, 1939, Serial No. 299,835

3 Claims. (Cl. 259—96)

This invention relates, as indicated, to treating apparatus for the particular treatment of materials and is an improvement of the process and apparatus of my prior Patent No. 2,042,880.

It will be observed that the apparatus of my said prior patent is characterized, in that the material to be mixed or treated is impounded centrally of a rotating member and then centrifugally attenuated as a continuous film over said member while mechanically supported on one side only, and whereby an intimate and thorough mixing and treating of the work material is effected.

The present invention is directed to an improvement in such apparatus whereby the components, or at least certain of them which are to be mixed or otherwise combined in a treating step, are separately attenuated into continuous films and such films then brought together to the accomplishment of the desired mixing or treating. It is, therefore, a principal object of my invention to provide an improved apparatus of the character described. Other objects of my invention will appear as the description proceeds.

To the accomplishment of the foregoing and related ends, said invention then consists of the means hereinafter fully described and particularly pointed out in the claims. The annexed drawings and the following description setting forth in detail certain means and one mode of carrying out the invention, such disclosed means and mode illustrating, however, but one of various ways in which the principle of the invention may be used.

In said annexed drawings:

Fig. 1 is a vertical sectional view partially in elevation of one form of the apparatus embodying the principles of my invention. Fig. 2 is a fragmentary transverse sectional view similar to a portion of Fig. 1, but showing an alternative form of construction of that portion of the apparatus thus illustrated; Figs. 3 and 4 are similar to Fig. 2, but respectively illustrating different modifications of the invention as illustrated in Fig. 1, and Fig. 5 is a fragmentary sectional view of a portion of the apparatus as illustrated in Fig. 4 showing a further modification in such construction.

Referring now more specifically to the drawings and more especially to Fig. 1, the apparatus comprising my invention includes a housing generally indicated at 1, provided with a bottom 2, a cover plate 3, and supporting legs 4. Body 1 is preferably cylindrical in form and the bottom

2 and top 3 are preferably curved in the manner illustrated, so that when the process is carried on under a vacuum or elevated pressure, the ends and side wall of the container housing the apparatus wherein the process is performed will be mechanically strengthened against failure.

Supported on the cover plate 3 is a housing member generally indicated at 5, which is provided with anti-friction bearings 6 and 7 rotatably supporting a vertically disposed hollow shaft 8. The hollow shaft 8 is at its lower end supported in an anti-friction bearing 9 carried by a bracket member 10. The bracket member 10 is supported from the side wall 1 by means of legs 11 and 12 and the supply pipe 13 which also serves as a supporting leg.

The upper end 14 of the housing 5 carries an electric motor 15 which drives the shaft 8 through the flexible coupling 16.

Supported in spaced relation on the hollow shaft 8 are oppositely disposed substantially conform discs 17 and 18, preferably of different diameters and so arranged that the peripheral edge of the smaller disc lies in a plane which intersects the work surface of the larger disc. While in the drawings the larger disc has been illustrated as the upper one and the small disc illustrated as the lower one, nevertheless it is within the contemplation of my invention to reverse the position of these parts.

Mounted on the hollow shaft 8 and capable of movement axially with respect thereto, and positioned between the discs 17 and 18, are spreader members 19 and 20. These spreader members are annular in form, tapering to a rather sharp edge at their peripheries, and are resiliently forced apart and into engagement with their associated discs by means of a spring 21. One of the spreader members 19 or 20 may be provided with an anti-friction bearing, such as 22, through which the spring 21 acts so as to permit free relative rotation between the spreader members, if this should be necessary or desirable, since generally the spreader members 19 or 20 are capable of rotation relative to the hollow shaft 8.

The hollow shaft 8 is provided with two plugs 22 and 23 closing the passage therethrough at the points where these plugs occur.

In the regions respectively generally indicated by the reference characters 24, 25 and 26, the wall of the hollow shaft is provided with a plurality of openings therethrough for the purpose hereinafter more fully explained.

The housing 5 is enlarged, as indicated, around

the area 24 of the shaft 8, and the anti-friction bearings 6 and 7 are of the type providing a fluid seal. A supply conduit 21 is connected to the housing 5 for the purpose of introducing some of the material to be treated to the apparatus.

Interiorly of the housing 1 and supported from the cover plate 3 by suitable depending brackets 3a, there is provided an annular deflecting ring 28 adjacent the peripheral edge of the larger disc. A discharge conduit 29 is connected to the bottom 2 for the purpose of withdrawing from the apparatus the material which has been treated. A conduit 30 is connected to the top 3 of the apparatus through which the space defined by the housing 1 may be evacuated so that the treating process may be carried on in a vacuum or alternatively a treating fluid, such as a gas under pressure may be introduced to the apparatus through the conduit 30.

The function of operation of the above described form of apparatus is briefly as follows:

The motor 15 is energized driving the discs 17 and 18 and their associated spreader members 19 and 20. A portion of the material to be treated, or more particularly one component of the desired ultimate mixture, is introduced to the apparatus through the conduit 27 and another portion of the material is introduced to the apparatus through the conduit 13. The material which flows through the conduit 27 passes into the space around the hollow shaft 8 defined by the housing 5. It flows through the openings 24 downwardly through the shaft 8, and is discharged through the openings 25 into the space between the spreader member 19 and its associated disc 17. Pressure of the material in this last defined space causes the spreader member 19 to move away from its associated disc 17, and since the latter is rotating at a relatively high speed, the material thus liberated will pass outwardly over the under face of the disc 17 in the form of a highly attenuated continuous film which is mechanically supported on one side only.

Similarly, that portion of the material which is introduced to the apparatus through the conduit 13 passes upwardly through the lower end of the hollow shaft 8 and is discharged through the openings 26 into the space between the spreader member 20 and its associated disc 18, from whence it flows outwardly over the upper surface of the disc 18 in a highly attenuated continuous film mechanically supported on one side only.

It is important to note that in carrying out the operation of the apparatus in the preferred manner in practicing the process of my invention, the outer periphery of the disc 18 is spaced sufficiently from the lower surface of the disc 17, so as to, in no way, interfere either with the passage of the thin film outwardly over the disc 17 or the discharge of the thin film from the periphery of the disc 18. The film which flows outwardly across the under face of the disc 17 from the central portion thereof therefore passes undisturbed past the peripheral edge of the disc 18. The continuous film which is discharged from the peripheral edge of the disc 18, however, flows on to the under face of the disc 17, due to the overlapping arrangement of the discs, and is there instantly and completely intermingled with the original film generated on the disc 17. While not illustrated in the drawing, it is within the contemplation of my invention to alter the slope of the active face of the larger disc at the point

where the continuous film from the smaller disc is discharged thereto, so as to compensate for the increased thickness in film, if this should be necessary in treating particular types of materials. Thus, the disc 17 in the annular area between its peripheral edge and the area where the film from the smaller disc 18 is delivered thereto, may be curved outwardly at a different and preferably a greater angle than the central portion of the disc 17. If the mixing of the two attenuated films is to be increased, or if the film from the smaller disc is of such a nature that it will not be picked up readily by the larger disc, then the outer peripheral area of the larger disc just defined may be disposed at an angle more acute to the axis of its rotation.

The mixed and/or treated material is discharged from the peripheral edge of the disc 17 in the form of a continuous film onto the deflecting ring 28 which deflects such continuous film, without breaking it up, downwardly against the side wall 1 so that the film may flow downwardly into the collecting chamber at the bottom of the apparatus.

In making a mixture of two components, or in treating one material with another, such two components will be respectively admitted to the apparatus through the conduits 13 and 27, to be later brought together in the form of highly attenuated continuous films in the manner above described. When a mixture of more than two components is to be made, or if, for example, a mixture is to be treated by means of an additional component, such groups of components may be respectively admitted to the apparatus through the conduits 13 and 27. If the treating process carried out by the apparatus involves a reaction, then generally the respective phases contributing to such reaction will be admitted through the separate conduits 13 and 27, respectively, and not brought together until they have been attenuated, as described.

The above described apparatus is particularly suitable for use in carrying out a process of treating materials where it is essential that there be a complete dispersion of one component in the other immediately the components are brought together, so as to preclude against over-treating certain portions of one or the other component which might result if there was even slight delay in effecting complete dispersion.

While only one pair of discs, i. e., a large disc and a smaller disc, has been illustrated, it is nevertheless within the contemplation of my invention to employ more than two such discs in carrying out my process if it should be desirable to attenuate more than two components before bringing them together. This may be readily accomplished by employing either an additional smaller disc, the peripheral edge of which will discharge onto the active surface of the larger disc, or by the use of a disc larger than 17, for example, onto which the latter disc will discharge.

In Figs. 2, 3 and 4 are illustrated modifications of the attenuating discs 17 and 18 and in the following description of the modifications thus illustrated, the same reference characters will be employed to designate like parts of the structure illustrated in Fig. 1 with sub-scripts *a*, *b*, and *c* employed respectively to designate similar parts which are not fully identical.

Referring now more specifically to Fig. 2, the lower attenuating disc 18a instead of being fixedly mounted on the shaft 8 is mounted thereon for

axial movement relative thereto and urged upwardly by means of a spring 31, the lower end of which bears on a collar 32 mounted on the shaft 8. The spring 31 is strong enough to normally maintain the peripheral edge of the disc 18a in engagement with the lower face of the disc 17, but yieldable so that the centrifugal force acting on the film which flows outwardly over the lower face of the disc 17 is effective to displace the disc 18a downwardly to permit the escape of such film outwardly over the attenuating surface of the disc 17. It will be observed, therefore, that the action of disc 18a in its peripheral edge is the same as the action of the spreader or baffle members 19 and 20 in providing an annular orifice for the projection of a continuous film over the radially outer portion of the attenuating surface on the larger disc.

In Fig. 3 the discs 17 and 18 are arranged and constructed as illustrated in Fig. 1. In addition, the shaft 8 has slidably mounted thereon a spider 33 which carries an annular ring 34. The spider 33 is forced upwardly by means of a yieldable spring 35, and such spring is strong enough to normally maintain the spreader 34 in engagement with the lower face of the upper disc 17, but will permit such ring to be displaced for the escape of a continuous film between the ring and disc 17 under the centrifugal force generated during the operation of the apparatus.

In Fig. 4 the upper disc 17c is smaller in diameter than the lower disc 18. Loosely mounted on the periphery of the disc 17c is a ring 36 which by gravity normally rests on the upper or operative face of the lower disc 18. An annular flange 37 around the peripheral edge of the disc 17c maintains the ring 36 in assembled relation in the apparatus. If desired a flat leaf spring of conventional construction might be inserted between a flange 37 and the ring 36 if the nature of the material being treated or the conditions of operation of the apparatus requires that the ring 37 bear against the disc 18 with greater force.

In the construction illustrated in Fig. 4, the lower spreader or baffle member 20c is permitted to rest by gravity on the lower disc 18 so that its operation is much like the operation of the gravity actuated spreader ring 36. When such construction is employed, a collar 38 secured to the shaft 8 serves as an abutment for the spring 21c by which the upper baffle 19c is maintained against the lower face of the upper disc.

In Fig. 5 has been illustrated a structure similar to Fig. 4, but in which an annular leaf spring 39 is interposed between the flange 37d and the ring 36d. This annular leaf spring 39 is of sinuous form so that the distance between the planes defined by different components of the spring is less, however, than the normal distance between the ring 36d and the flange 37d. Thus the ring 36d is permitted to rise by gravity as the merged film passes thereunder until a pre-determined thickness of film is produced determined by engagement between the spring 39 and the flange 37d. Any increase in thickness of the film which passes under the flange 36d can be accomplished only by a deformation of the spring 39. This apparatus will have obvious utility in the treatment of certain types of materials and under certain conditions of operation of the machine. In the structures of each of Figs. 4 and 5, the lower face 40 of the disc 17d and the lower face 41 of the ring 36d are so formed that when the ring 36d rests on the lower disc 18, a substantially continuous surface, is presented for the

passage of the attenuated film over the operative face of the disc 17d. As the ring 36d rises, there will be, of course, a slight discontinuation in such surface; however due to the inclination of the surface 41, the film is immediately picked up without there being an opportunity for the film to break up and atomize.

The edges of all of the spreader rings and baffles, i. e. such as 19, 20, 34, 36 and 38d should be relatively sharp, i. e. the included angle should be less than 45°. If a greater angle is employed, the film has a tendency to curl up behind the edge of the spreader ring or baffle, and result in the projection of droplets tending to disrupt the continuous character of the film.

From an inspection of the structures illustrated in Figs. 2 to 4, it will be observed that by the provision of expedients there disclosed and particularly described, I have provided an annular orifice at the annular area where the separately attenuated films are merged so as to insure that the merged film will be caused to flow outwardly over the radially outward portion of the operative face of the larger disc in a true continuous film. An auxiliary expedient of this character is particularly desirable where the speed of operation of the apparatus or the character of the material being treated is such that the impingement of the attenuated film from the smaller disc onto the partially attenuated film on the larger disc has a tendency to cause the material to ricochet and leave the operative face of the larger disc. By employing any of the expedients as illustrated in Figs. 2 to 4, the material being treated is maintained at all time as a coherent mass, i. e. it is at no time broken up or atomized, this being a characteristic of the prior art machines which my improved apparatus is particularly designed to avoid.

The apparatus comprising my invention is adapted to a wide variety of uses, among which may be named the following:

The blending or mixing of oil stock such as petroleum oils; the mixing of liquids and slurries such as, for example, treating a fatty oil with a slurry of treating clay; the alkali treatments of fatty oils for the purpose of neutralizing the free fatty acids contained therein; the acid treatment of resins, etc.

The apparatus herein described is particularly suited for the purpose of carrying out my process for promoting reactions, which reactions may, as hereinafter indicated, be either chemical, physical or physico-chemical.

Where the reactants are contained in separate phases, for example, two immiscible liquids, or a solid and a liquid, or a liquid and a plurality of solids, reaction can only take place at the contact surfaces between such phases.

My use of the term "phase" is based on the understanding of that term as generally accepted in the application of Gibbs' Phase Rule.

I have found that the thickness of the film into which the phases containing the reactants is attenuated as referred to in the foregoing enumeration of specific examples plays an important role in carrying out my invention. In carrying out the process comprising my invention, this attenuated film will preferably be reduced to a thickness of not substantially in excess of .0007 inch, and such film caused to flow relatively to the surface mechanically supporting the same on one side only, by speed not substantially less than 25 feet per second. The speed figure given above is the speed of relative movement between the

film and the supporting means at the time the film is attenuated to substantially its smallest thickness and at the time of greatest relative movement between the film and supporting surface.

It will be observed that this attenuated film, during which the reaction is primarily promoted, is mechanically supported on one side only so that the phases of the reaction are brought into intimate relation with each other by virtue of the fact that the attenuated film passes over the solid surface at a relatively high speed and the frictional resistance between the film and the supporting surface is largely responsible for the action which takes place. The impact of the finely attenuated film on the collecting ring or wall of the vessel also plays a large part in producing the desired results.

When all of the materials forming the reaction mass are in a liquid or fluid state, the thickness to which the film is attenuated is sometimes determined by the viscosity of the liquid film, the temperature at which the reaction is promoted, as well as the nature of the reaction itself. Generally, with liquids which have a viscosity between 50 seconds and 1,000 seconds Saybolt Universal at 100 degrees F. and when the nature of the reaction is such as to not in itself cause any material disturbance in the film, the thickness to which the film should be desirably attenuated will preferably be between .0001 and .0007 inch.

When the reaction mass contains a solid in finely divided form, then the size of such solids will generally dictate the most desirable thickness for the attenuated film. In general, the attenuated film which contains finely divided solids should be at least as thick as the solid particles themselves and generally, superior results will be secured if the thickness of the film does not exceed three times the diameter of such solid particles.

The herein described apparatus is particularly suited in carrying out processes in which the phases of the reaction to be promoted should be completely intermixed or contacted within the shortest possible time, in order that there may not be an over-treatment of portions of one phase by the other before the latter becomes completely dispersed in the film. By the use of the herein described apparatus, the two phases may be separately attenuated on the separate disks and then brought together as thinly attenuated continuous films which, by immediate further attenuation of the merged film, result in a uniform and immediate completion of the desired reaction.

Most of the uses above described are desirably carried out in apparatus, such as is disclosed herein; however, when the reaction phases are such that they may be safely intermingled prior to attenuation of the mass into a continuous film for the purpose of promoting and completing the reaction, then apparatus such as is disclosed in my issued Patent No. 2,042,880 may be employed.

By so finely attenuating the reaction phases or components of the mixture in the fashion above described, it is possible to develop latent properties of the composition so as to improve its usefulness for the purposes for which it is designed. Thus, for example, the effectiveness of a particular component usually employed in small percentages in a finished composition may be considerably improved so that smaller amounts of such components may be employed to attain the same degree of effectiveness.

By the employment of my process, materials may be blended into a stable form of composition which is not possible by known methods of the prior art. For example, in the blending of an addition agent with an oil, which addition agent is not completely soluble or miscible in the oil, a composition produced by ordinary mixing methods under elevated temperatures will result in the production of a composition from which 5 the addition agent separates on standing. When such composition is blended in accordance with the process of my invention, i. e., by passing it at a very high speed and in the form of an extremely thin film over means mechanically supporting the same on one side only, a composition is produced which will not separate on standing. As an explanation of this phenomena, it is believed that when the addition agent is caused to flow in finely attenuated form over one side only 10 of the supporting disk, the addition agent is dispersed in the body material in extremely finely divided form. These very small particles of addition agent, in passing over one side of the disk, gather electro-static charges which are all of 15 like polarity so that these particles, when the composition is finally collected in a body will, due to their similar polarity, repel each other so that by virtue of their electro-static charges and mutual repelling effect on each other, are held 20 in a stable form of dispersion. This theory has been verified by the formation of a dispersion of the character described and then immersing 25 in such dispersion an electro-statically charged rod which, after removal from the immersion will 30 be found to have collected on its surface a layer of the material which was dispersed.

This application is a continuation-in-part of my copending applications Serial Numbers 194,015, filed March 4, 1938 and 203,976, filed 35 April 23, 1938.

Other modes of applying the principle of my invention may be employed instead of the one explained, change being made as regards the 40 means and the steps herein disclosed, provided those stated by any of the following claims or 45 their equivalent be employed.

I, therefore, particularly point out and distinctly claim as my invention:

1. In a device of the character described, an 50 assembly comprising a pair of relatively smaller and larger rotatable members respectively provided with facing oppositely inclined annular film-supporting and attenuating surfaces, means 55 arranged centrally of each of said members providing an annular orifice for the projection of the material to be treated in continuous films respectively onto said attenuating surfaces, said members so arranged that a film centrifugally projected from said smaller member flows, as a 60 continuous film, into the film on the attenuating surface of said larger member in an annular area between the radially inner and outer boundaries of such larger member, an annular 65 baffle member adjacent the periphery of said smaller member and cooperating with the adjacent attenuating surface of the larger member to provide an annular orifice for the projection of said merged films in a continuous film over the radially outward portion of the attenuating 70 surface on said larger member.

2. In a device of the character described, an 75 assembly comprising a pair of relatively smaller and larger rotatable members respectively provided with facing oppositely inclined annular

film-supporting and attenuating surfaces, said members so arranged that a film centrifugally projected from said smaller member flows, as a continuous film, into the film on the attenuating surface of said larger member in an annular area between the radially inner and outer boundaries of such larger member, an annular baffle member adjacent the periphery of said smaller member and cooperating with the adjacent attenuating surface of said larger member to provide an annular orifice for the projection of said merged films in a continuous film over the radially outward portion of the attenuating surface on said larger member.

3. In a device of the character described, an assembly comprising a pair of relatively smaller and large rotatable members respectively provided with facing oppositely inclined annular

film-supporting and attenuating surfaces, said members so arranged that a film centrifugally projected from said smaller member flows, as a continuous film, into the film on the attenuating surface of said larger member in an annular merging area between the radially inner and outer boundaries of such larger member, said smaller member having a baffle member cooperating with the attenuating surface of said larger attenuating member to provide an annular orifice for feeding the merged films onto the annular attenuating area of said larger member located radially outwardly of said orifice, said annular attenuating area being operable to attenuate the merged films to complete the mixing action of the material.

MEAD CORNELL.
